ELECTRIC LAMP

Tsuneto Ohara, Kotaro Enomoto, and Ko Honda,
Tokyo, Japan, assignors of one-fifth to Kan-
ichiro Matsuki, Tokyo, Japan

Application March 3, 1928. Serial No. 258,955

1 Claim. (Cl. 176—32)

This invention relates to incandescent electric lamps, more particularly, to an incandescent electric lamp having its bulb portion and neck portion formed of a single piece of glass, the terminals of the filament being so mounted that one of them is disposed on the periphery of the neck portion and the other is mounted on the end of the neck portion. It is the object of the present invention to provide an incandescent electric lamp which is more durable and lower in cost than present forms of electric lamps and can be handled with greater convenience than the types of electric lamps now known.

Incandescent electric lamps having their bulb portion and neck portion integral have been proposed before. Usually, however, such lamps have been so constructed as to necessitate a spring member, or other metal member, for establishing contact with the filament. In consequence, such bulbs have been quite expensive because of the greater labor and care required in their manufacture. The advantages inherent in the elimination of the usual metal base have therefore been more than balanced by the disadvantages of the increased cost. The present invention, on the other hand, concerns the provision of an incandescent lamp having its bulb portion and its neck portion formed of a single piece of glass and having its filament terminals so mounted as to permit the use of the bulb in the usual form of lamp socket. The fact that the lamp bulb is formed of a single piece of glass, instead of a number of separate portions joined together, makes it considerably stronger and more durable than previous forms of lamp bulbs made entirely of glass and, furthermore, the mounting of the filament terminals in such a manner as to permit the use of the bulb in a standard socket, enables the use of the present improved type of lamp bulb on any and all occasions where the customary metal base lamp bulbs are ordinarily used. Being made entirely of glass, the present form of lamp bulb can be manufactured at a considerably lower cost than lamp bulbs requiring a metal base, and due to the smooth surface of the glass neck portion, a lamp bulb of the type contemplated by the present invention can be more readily mounted and disconnected from a lamp socket than the various forms of all glass lamps heretofore in use.

For a better understanding of the invention, reference is made to the accompanying drawing wherein:

Fig. 1 is a side view of a lamp in accordance with

55 the invention.

Fig. 2 is a longitudinal section of the lamp shown in Fig. 1.

Referring to the drawing more in detail, the lamp is of the usual shape having a bulbous portion *a* enclosing the filament, and a neck por-

tion *b* formed integral with the portion *a* and provided with a screw threaded surface *d* to permit the mounting of the bulb in a customary form of socket. As shown in Fig. 2, the neck portion *b* and the bulbous portion *a* are integral and formed of a single piece of glass.

The filament is supported inside the bulb *a* by means of a filament supporting tube extending inwardly into the neck portion. In its final form, shown in Fig. 2, the filament supporting tube is joined to the neck portion *b* at the end thereof so as to provide a continuous structure of glass. The lead wires *c* from the filament extend through the supporting tube toward the end of the neck portion *b*, one of the lead wires terminating in a terminal mounted on the periphery of the neck portion and the other lead wire ending in a terminal so mounted as to close the open end of the supporting tube and provide a substantially flat base for the bulb.

As is evident from the drawing, the bulbous portion *a* and neck portion *b* are continuous and so formed as to provide a smooth outer surface having neither a step nor a shoulder of the nature common to the all glass lamps heretofore proposed. Furthermore, the lead wires *c* are so mounted on the neck portion *b* as to eliminate the necessity for any metal contact rings or plugs, thereby simplifying the construction of the lamp. If desired, the neck portion *b* may be frosted to improve the lighting characteristics of the lamp.

We claim:

A glass incandescent electric lamp having all except the filament and terminals in one piece, comprising a bulbous portion, said bulbous portion merging into a cylindrical neck portion having external screw threads formed integrally therewith for fitting directly into a lamp socket, the end of said neck beyond the screw threads being turned inwardly to form a hollow filament supporting tube which extends through said neck portion, a filament within the bulb, and a pair of lead wires extending from the filament through the filament supporting tube, one of said lead wires passing through the glass where the neck portion turns inwardly to form the hollow tube and terminating in a filament terminal on the neck portion adjacent the socket end thereof and beyond the screw threads, the other lead wire terminating in a filament terminal located substantially at the center of the inturned end portion of the neck.
